Attorney

UNITED STATES PATENT OFFICE.

EDWARD J. ZAHNER, OF LAPORTE, INDIANA.

METALLIC-DOOR SEAM.

Application filed December 7, 1921. Serial No. 520,481.

To all whom it may concern:

Be it known that I, EDWARD J. ZAHNER, a citizen of the United States, residing at Laporte, in the county of Laporte and State 5 of Indiana, have invented certain new and useful Improvements in Metallic-Door Seams, of which the following is a specification.

The invention relates to metallic doors, 10 and has for its object to provide in combination with a metallic door seam filling so shaped that it will be held against breakage and displacement during the slamming or jarring of the door, thereby preventing 15 marring or damage to the finish of the door.

A further object is to provide a metallic door comprising stiles substantially U-shaped in horizontal cross section and having their flanges extending toward each other and slightly spaced from the ends of flanges of rails, thereby forming a seam space for the reception of cement and to provide vertically disposed channels disposed within the stiles and having their 25 flanges in registration with the seams and provided with vertically disposed channels arching the seams, thereby forming a pocket for the reception of cement which will be larger than the seam and will prevent the 30 cement within the seam from falling outwardly. Also to so construct the stiles and rails that easy access may be had for spot welding the flanges of the channels to the flanges of the stiles and rails.

35 Also to so construct the stiles and rails that easy access may be had to weld the panel molding to the panel, thereby allowing the miter joints of the molding to be started together on the inside, thereby obviating the necessity of cleaning and shaping the joint which is now common practice 40 in metallic door construction.

With the above and other objects in view the invention resides in the combination and 45 arrangement of parts as hereinafter set forth, shown in the drawings, described and claimed, it being understood that changes in the precise embodiment of the invention may be made within the scope of what is 50 claimed without departing from the spirit of the invention.

In the drawing:—

Figure 1 is a front elevation of the metallic door.

55 Figure 2 is a horizontal sectional view through one of the joints between one of

the stiles and rails taken on line 2—2 of Figure 1.

Figure 3 is a vertical detail sectional view through one of the corners of the door, 60 taken on line 3—3 of Figure 2.

Referring to the drawings, the numerals 1 and 2 designate the stiles of the door, and 65 3 and 4 the top and bottom rails of the door. The stiles 1 and 2 are preferably U-shaped in horizontal cross section and have their flanges 5 inwardly disposed and adjacent the ends 6 of the rails 4, and in the same vertical plane as the rails 4 and 3, but slightly spaced from the ends thereof thereby forming a vertically disposed space between the adjacent ends of the flanges 5 and the rails for the reception of cement 8. It has been found that if provision is not made for holding the cement in the 75 spaces 7, that the cement is dislodged incident to the slamming or jarring of the door, and consequently the high finish on the door, at its joint, is marred, and the door rendered unsightly. To prevent dislodgment of the 80 cement 8, and at the same time secure the stiles 1 and 2 to the rails 3 and 4, U-shaped channel members 9 are placed within the stiles and with their flanges extending inwardly and in registration with the spaces 85 7, said flanges being designated by the numerals 10. The flanges 10 are provided with inwardly struck vertically disposed ribs 11, which form vertically disposed grooves 12, which arch the spaces 7 from points spaced 90 from the sides of the spaces, thereby forming an enlarged vertical disposed pocket for the reception of the body portion 13 of the cement 8, which body portion, on account of it being larger and wider than the spaces 7, 95 prevents the cement 8 in the spaces 7 from falling outwardly or being dislodged incident to jarring or slamming of the door.

After the cement 8 and the enlarged portion 13 thereof is in place, the seam is 100 cleaned and the door then enameled or otherwise finished. The flanges 10 of the channel members 9 are preferably spot welded at 14 to the flanges 5 of the stiles 1 and 2 and to the rails 4, thereby providing a rigid 105 structure. It will be seen that access may be easily had to the interior of the rails 4 and 3, and to the stiles 1 and 2 for spot welding purposes. By so constructing the door the door may be easily assembled, and 110 also quickly assembled. In a door so constructed the miter joints 15 may be soldered.

on the inside thereby joining the molding 16 in such a manner that it will not be necessary to finish the outside joints of the miters and that the panels 17 may be spot welded 5 as at 18 to the molding 16. The molding 16 may be secured within the door in any suitable manner, however for purposes of illustration the panel has been shown as supported by the moldings engaging the edges 10 of the flanges 5 of the stiles 1 and 2, and the rails 3 and 4, as clearly shown in Figure 3.

From the above it will be seen that a metallic door is provided, which is simple in construction and which may be easily and 15 quickly assembled, access being had easily to all parts thereof to spot weld the panel molding to the panel, which is particularly of great advantage in permitting the miter joints of the panel molding to be soldered 20 together on the inside by applying a fusible wire along the joints and applying a gas flame.

The invention having been set forth what is claimed as new and useful is:—

25 1. A metallic door comprising stiles U-shaped in horizontal cross section and having their flanges extending toward each other, rails adjacent the ends of the stiles and having their ends adjacent the inner edges of the flanges of the stiles, U-shaped channel members disposed within the stiles and between the rails, the flanges of said channel members registering with the seams formed between the stiles and the rails, said 30 flanges being provided with vertically disposed grooves arching the seams, thereby forming in connection with the spaces between the stiles and rails, chambers T-shaped in cross section for the reception of cement, said flanges of the channel members 35 being secured to the stiles and rails.

40 2. The combination with a metallic door having seams formed at adjacent edges, of

a member arching the seam on the interior thereof and of greater width than the seam, 45 thereby forming a cement receiving chamber having an enlarged inner side.

3. The combination with a metallic door having oppositely disposed seams formed by adjacent flanges, of means for securing said flanges together and forming an enlarged inner portion to the seams for the reception of cement, said means comprising a member having flanges in registration with the seams and provided with vertically disposed 50 grooves arching the seams, said flanges being secured to the adjacent flanges forming the seam.

4. The combination with a metallic closure for a building, said closure having a seam formed by spaced adjacent flanges, of means for forming a substantially T-shaped cement receiving chamber at the seam, said means comprising a member secured to the spaced flanges and provided with a groove 55 arching the adjacent edges of the flanges.

5. The combination with a metallic building closure formed from metallic members between which members cement seams are formed, of means whereby said seams may 60 be formed with inwardly disposed enlargements, thereby preventing dislodgment of the cement.

6. The combination with a metallic building closure formed from adjacent metallic 65 members between which members a cement seam is formed, of means whereby said cement seam will be prevented from displacement, said means comprising means disposed adjacent the seam and forming a pocket 70 whereby an inwardly disposed enlargement will be formed integrally with the cement between the adjacent metallic members.

In testimony whereof I affix my signature.

EDWARD J. ZAHNER.
